Assistant Examiner — Richard Kearney

(57) **CLAIM**

The ornamental design for a tube wiring harness restraint, as shown and described.

DESCRIPTION

FIG. 1 is a front perspective view of a tube wiring harness restraint showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear view thereof;

FIG. 8 is a rear perspective view of the tube wiring harness restraint; and,

FIG. 9 is an exploded view of the tube wiring harness restraint in an exemplary environment of use.

The broken lines shown in FIG. 7 illustrate portions of the tube wiring harness restraint that from no part of the claimed design. The broken lines shown in FIG. 9 illustrate environmental structure that forms no part of the claimed design.

1 Claim, 7 Drawing Sheets
